CLAIM

The ornamental design for a vibrator attachment for power tool, as shown and described.

DESCRIPTION

FIG. 1 is a perspective view of a vibrator attachment for power tool, showing our new design;

FIG. 2 is a front view of the vibrator attachment for power tool;

FIG. 3 is a rear view of the vibrator attachment for power tool;

FIG. 4 is a right side view of the vibrator attachment for power tool;

FIG. 5 is a left side view of the vibrator attachment for power tool;

FIG. 6 is a top view of the vibrator attachment for power tool; and,

FIG. 7 is a bottom view of the vibrator attachment for power tool.

The broken lines showing in the figures are included for the purpose of illustrating portions of the vibrator attachment for power tool that form no part of the claimed design. The dash-dot lines showing in the figures are included for defining the bounds of the claimed design that form no part thereof.

1 Claim, 6 Drawing Sheets
